(57) **CLAIM**

The ornamental design for a combined spout flame arrester and adapter as shown and described.

DESCRIPTION

FIG. 1 is an isometric view of the combined spout flame arrester and adapter of this invention;

FIG. 2 is a front view thereof;

FIG. 3 is a back view;

FIG. 4 is a left side view;

FIG. 5 is a right side view; and,

FIG. 6 is a bottom view of the invention.

1 Claim, 2 Drawing Sheets
